UNITED STATES PATENT OFFICE.

LOUIS H. SHOEMAKER, OF PATERSON, NEW JERSEY.

LOCOMOTIVE TURN-TABLE.

SPECIFICATION forming part of Letters Patent No. 662,031, dated November 20, 1900.

Application filed March 16, 1900. Serial No. 8,911. (No model.)

To all whom it may concern:

Be it known that I, LOUIS H. SHOEMAKER, a citizen of the United States, residing at Paterson, in the county of Passaic and State of New Jersey, have invented certain new and useful Improvements in Locomotive Turn-Tables, of which the following is a specification.

My invention relates to turn-tables operated by other than manual power, and especially to those operated by electric motors.

The objects of my invention are, first, to provide a means by which either end of an ordinary locomotive turn-table may rest directly upon a solid support while the turn-table is being loaded or unloaded and then lifted clear of the support to permit of its being turned; second, to provide a means by which the power from a motor attached to the turn-table may be applied to the ends of the turn-table to revolve it horizontally about its center, and, third, to automatically center the turn-table with the track by which it is to be loaded or unloaded and hold it in position during the operation. I accomplish these objects by providing a carriage at each end of the turn-table and suitable mechanism for raising and lowering its ends from these carriages. A latch with a wedge-shaped end actuated by the above mechanism enters a bell-mouthed orifice and centers and secures the table. One of the wheels of each carriage is to act as a drive-wheel and is to be geared to a motor attached to the turn-table in such manner as not to interfere with raising and lowering the ends of the table.

The following is a description of my invention, reference being had to the accompanying drawings, in which—

Figure 1 is an elevation of the carriage, a transverse section being taken of the turn-table on the line A A, Fig. 2. Fig. 2 is a transverse section of the carriage, a longitudinal section being taken of the turn-table on the line B B, Fig. 3. Fig. 2 shows in elevation the mechanism for raising and lowering end of turn-table and operating-latch. Fig. 3 is a horizontal section of carriage and turn-table and shows the principal parts in plan.

The principal parts of the carriage are the girder G, the vertical shafts V, and the angle-irons A, connected so as to constitute a truss supported by the drive-wheel D and the trail-

ing wheel T. The vertical shafts V pass through bearings on the turn-table and serve to hold the carriage in a vertical position.

55

The links l turn on pins at the top, which are carried in bearings secured to cross-girders in the turn-table. At the bottom they turn on pins carried in bearings secured to the girder G. The links l are operated by the bars b, pinned to the levers r, which are keyed to the shaft s. The shaft s is supported in bearings attached to turn-table and is actuated by the lever L and bar B. The bar B may be actuated by a mechanism to which 60 the power of the driving-motor can be temporarily applied by means of a clutch or otherwise or it may be actuated by an independent motive power. The lever v, keyed to the shaft s, operates the latch h by means of the 65 slotted bar n and the counterweighted bent lever t. The spur-wheel W is keyed to the drive-wheel axle and is actuated by the pinion p and driving-shaft S. The shaft S is supported by bearings attached to side of 70 turn-table.

75

The mechanism is shown in the position it would assume with both ends of turn-table lifted clear of the supports and ready for turning.

80

The carriage at one end only of turn-table is shown, the other being precisely similar. The bar B, extending continuously from one carriage to the other, operates the links so as to raise one end and lower the other with the 85 same movement.

What I claim to be new in my invention, and desire to secure by Letters Patent, is—

1. In an ordinary turn-table, consisting of two girders continuous over a center pivot 90 about which it turns both vertically and horizontally, carriages for supporting ends of turn-table consisting of a girder supported by wheels on a circular track to which the ends of turn-table are flexibly connected vertically 95 and rigidly connected horizontally.

2. In an ordinary turn-table, consisting of two girders continuous over a center pivot about which it turns both vertically and horizontally, carriages, one at either end of the 100 table, each consisting of a girder supported by two wheels on a circular rail, and each connected to an end of the turn-table in such manner that the carriage is maintained in a

vertical position by the turn-table and rigidly connected to it horizontally, while permitting the ends of the turn-table to be raised and lowered by flexible connections between 5 carriages and turn-table.

3. In an ordinary turn-table consisting of two girders continuous over a center pivot about which it turns both vertically and horizontally, with carriages at the ends resting 10 upon a circular track, said carriages connected to the ends of turn-table in a rigid manner horizontally but so as to permit the ends of turn-table to move vertically with respect to carriages, pairs of links flexibly connected 15 together, one link of each pair being flexibly connected to turn-table near its end and the other link being flexibly connected to carriage, and proper mechanism for actuating the joints of said pairs of links, so that by 20 one movement the links are operated at both ends of turn-table, raising one end and lowering the other with respect to the carriages, substantially as described.

4. In an ordinary locomotive turn-table,

with a carriage at each end to which the turn-table is rigidly attached horizontally and flexibly attached vertically, a mechanism consisting of the driving-shaft S, the pinion p, and the spur-wheel W, by which a suitable motive power may be applied to one of the wheels 25 of each carriage in such manner as not to interfere with raising and lowering ends of turn-table and by means of which the turn-table may be turned horizontally about its center, substantially as described. 30

5. In an ordinary turn-table flexibly supported at the ends from carriages as before described, with suitable mechanism for raising and lowering the ends of turn-table from 35 said carriages, a latch actuated in connection with said mechanism so made as to bring the turn-table track into alinement with the track on the edge of the turn-table pit and secure it in that position, substantially as described. 40
